SPECTACLE FRAME ORNAMENT OR SIMILAR ARTICLE

Harry Weissman, New Hyde Park, N. Y.

Application April 22, 1955, Serial No. 35,637

Term of patent 3½ years

(Cl. D57—1)

Fig. 2

Fig. 1

Fig. 1 is a front elevational view of a spectacle frame ornament or similar article showing my new design.

Fig. 2 is a side elevational view thereof.

The dominant features of the design reside in the portions shown in full lines.

I claim:

The ornamental design for a spectacle frame ornament or similar article, substantially as shown and described.
